UNITED STATES PATENT OFFICE.

DAVID WATTS WINSTANLEY, OF EGREMONT, ENGLAND, ASSIGNOR OF ONE-HALF TO WALTER HENRY TRAVERS, OF SEACOMBE, ENGLAND.

SWEEEPING BROOM OR BRUSH.

SPECIFICATION forming part of Letters Patent No. 716,161, dated December 16, 1902.

Application filed April 21, 1902. Serial No. 104,002. (No model.)

To all whom it may concern:

Be it known that I, DAVID WATTS WINSTANLEY, a subject of the King of England, and a resident of Egremont, in the county of 5 Chester, England, have invented new and useful Improvements in Sweeping Brooms or Brushes, of which the following is a specification.

This invention has reference to brooms or 10 brushes for sweeping surfaces, such as road or street and similar surfaces; but it is also applicable to other sweeping brushes or brooms having handles operated by both hands in a similar manner to similar sweeping-brooms.

This invention has for its object and effect 15 to provide improvements in connection with brooms or brushes of the kind referred to by which their useful life is prolonged and 20 their efficient action is retained throughout their useful condition—that is, both at commencement of use and after they have worn down a great deal—while at the same time the brush is more effective in its action and 25 is easily used.

The invention is illustrated in the accompanying drawings, which show two modifications according to this invention.

In the drawings, Figure 1 is a side elevation 30 and Fig. 2 is an end view, of one modification; and Fig. 3 is a side elevation, and Fig. 4 an end view, showing another modification.

According to this invention, between the 35 handle and the head of the brush, a spring or springs is or are introduced, which when the brush is pressed on the ground or surface, and pushed forward, allows it to move inward toward the sweeper, and then afterward when 40 lifted off the ground, springs back to its normal position.

Referring to the drawings, *a* represents the wooden head, and *b* the bristles, of an ordinary road or street or like sweeping-broom.

45 *c* represents two inclined sockets, in one of which the brush-handle *d* is introduced. These sockets *c* are oppositely arranged and

connected with the head *a* of the broom by a plate or bar *e*, which fits in a groove or recess *f* in the head.

In the construction shown in Figs. 1 and 2 the part *e* is of considerable depth, and is made in the form of a thin sheet-plate of steel, which constitutes a flat spring, whereby when the broom is pressed onto the surface and 50 pushed before the sweeper spring or elasticity is imparted to the broom and when raised from the surface it swings the broom to its normal position again. In this case the handle-carrier is secured in the broom by driving 55 the plate-spring *e* down into the wooden head *a*.

When the broom is worn somewhat and the bristles at one edge are longer than the other, the handle can be taken out of one socket *c* 60 and placed in the other, thereby reversing the position of the broom, with the result that the unevenness is worn off, and when it becomes uneven in the new position the handle may be again reversed, and so on by reversing the position of the broom in relation to the handle the bristles receive their 65 strain in opposite directions—first in one direction and then in the other—with the effect that their useful life is prolonged while the 70 amount of labor is reduced.

As regards the construction shown in Figs. 3 and 4, in this case the bar *e* is shorter, and the sockets *c* lie nearer the head *a* of the broom, the bar *e* resting in a groove *f*, in 80 which it is free to have a certain amount of rocking action. The spring or elasticity is obtained in this case by a spiral spring *e'*, extending between each of the sockets *c* and the head *a* and connecting them together. 85 The connection is effected by a hook *c'* or the like on the sockets *c* and a staple or pin *h*, driven into the wood broom-head *a* and to which the lower end of the springs are attached.

90 It is to be stated that the invention is not restricted to the particular form of spring or springs described and set forth with reference to the drawings, nor to the particular mode of

connecting the socket portion with the broom-head.

Having now described my invention, what I claim as new, and desire to secure by Letters

5 Patent, is—

The combination of a sweeping-brush head *a*, with the metal sockets *c*, a spring disposed between said sockets, and the broom-head, and a bar *e* connected with the end of the

sockets *c*, and bearing on the upper surface to of the head *a*, substantially as described.

In witness whereof I have hereunto set my hand in presence of two witnesses.

DAVID WATTS WINSTANLEY.

Witnesses:

JOHN H. WALKER,
LEONARD GRAWLEY.
